UNITED STATES PATENT OFFICE

2,601,044

TORQUE WRENCH

William H. Mayer, Fort Wayne, Ind.

Application January 6, 1949, Serial No. 69,565

1 Claim. (Cl. 81—52.4)

1

This invention relates to a torque wrench. The invention is particularly useful in connection with a wrench which is adjusted for exerting limited torque in the rotating of a nut or other object, the structure permitting ratcheting of the wrench shaft during the operation.

An object of the invention is to provide a torque wrench of few parts which is effective for exerting limited torque in the turning of an object while at the same time permitting ratcheting of the shaft during the turning operation. A further object is to provide a unitary torque wrench shaft equipped with means cooperative with a spring plunger for exerting a desired amount of torque upon an object to be rotated, while at the same time permitting easy ratcheting of the shaft in the operation of the wrench shaft. A further object is to provide a novel plunger structure cooperating with a cam wrench and a shaft for effecting turning of an object while at the same time permitting the ratcheting of the shaft in such operation. Other specific objects and advantages will appear as the specification proceeds.

The invention is shown in an illustrative embodiment by the accompanying drawing, in which—

Fig. 1 is a perspective view of a wrench structure embodying my invention; Fig. 2, a transverse sectional view; Fig. 3, a sectional view, the section being taken as indicated at line 3—3 of Fig. 2; and Fig. 4, a perspective view of the wrench shaft and associated plunger spring and cap parts employed in the wrench embodying my invention.

In the illustration given, 10 designates a casing which may be formed of metal or other suitable material. In the illustration given, the casing 10 provides a tubular casing portion 11 providing a passage receiving the wrench shaft 12, and a tubular portion 13 providing a passage intersecting the wrench shaft passage, as shown more clearly in Figs. 2 and 3. The casing 10 is shown in the form of a T but it may be in the shape of an L or any other desired shape.

The wrench shaft 12 is equipped at its outer end with a reduced squared end 14 and the end may be provided with a spring-urged ball 15, as shown more clearly in Fig. 2. The end 14 is adapted to be inserted in a square socket of the nut or other part to be rotated. It will be understood that the end 14 may be of any desired shape for use in engagement with a socket or other part to be engaged for rotating an object.

2

To retain the shaft 12 within the casing extension 11, a pin 16 may be passed through the casing portion 11 so as to engage an annular groove 17 formed within the shaft 12.

The inner end of the shaft 12 is provided with cam surfaces 18, as shown more clearly in Figs. 3 and 4. Each of the cams 18 is provided with a ridge portion 19 which is rather steeply inclined and with a slightly inclined and partially downwardly inclined ratchet portion 20. Between ridge portions 19 and ratchet portions 20 there are provided depressed portions 28 of reduced radius as seen more clearly in Fig. 3. It will be noted that ridge portions 19 provide surfaces of rapidly increasing radius, while ratchet portions 20 provide surfaces of gradually increasing radius.

Cooperating with the cam surfaces is a plunger 21 having an elongated rounded end 22 bearing 20 against the cam surface 18. The elongated or ridged end 22 cooperates with the sharply inclined portion 19 of the cam 18 for rotating the shaft 12, while the slightly inclined portion 20 of the cam permits the plunger end 22 to 25 ratchet over said portion 20 as the casing 10 is rotated in a counter-clockwise direction as shown in Fig. 3.

A spring 23 normally urges the plunger 21 toward the cam portions 18 of shaft 12. The spring is tensioned by means of a screw cap 24 having a slot 25 therein for receiving the end of a screwdriver, and on its inner side the cap 24 may be provided with a pin 26 received within the spring 23.

In the operation of the structure, the shaft 12 is placed within the tubular casing portion 11 and secured therein by driving the pin 16 through the casing portion into engagement with the annular groove 17. The shaft 12 may thus 35 rotate with respect to casing portion 11 while being held against longitudinal movement.

The spring-urged plunger 21 engages the cam surfaces 18 and when the casing 10 is rotated in one direction so that the ridge portion 19 of the cam bears against the plunger end 22 while it is seated within the depressed portion 28, the shaft 12 is held against turning and the desired amount of turning force is applied to the nut or other object to be rotated. On the 45 other hand, when the casing 10 is rotated in the opposite direction the handle casing 10 carries the plunger end 22 out of the depressed portion 28 over the cam surface 20 to permit it to engage the ridge portion 19 of the next cam surface 18. Thus, as one looks at the struc-

ture shown in Fig. 3, the casing 10 may be rotated in a clockwise direction to effect turning of the shaft 12 and the nut engaged thereby, and then the casing 12 may be swung in a counter-clockwise direction with the plunger end 22 sliding over the cam portion 20 until the next ridge portion 19 is engaged, at which time the shaft 12 may be again rotated to the left to effect another partial turning of the nut or other object to be rotated.

After the nut has been tightened to the desired point, the ridge portion 19 of the cam 12 is no longer effective in locking the shaft 12 to the casing 10, and the plunger 21 yields or ratchets over the cam portion 19. The wrench thus becomes inoperative for further turning movement of the nut. Should it be desired to increase or diminish the torque of shaft 12, a screwdriver or other blade may be applied to the slot 25 of cap 24 and the cap may be adjusted longitudinally of the casing portion 13 to increase or diminish the compression of spring 23. The threaded cap 24 engages a relatively long threaded portion 27 in the casing portion 13 so that substantial adjustment can be effected by rotating the member 24.

The casing 10 in the T-shape illustrated is useful in that the T portion of the casing provides a handle by which the tubular portion 11 may be rotated in both directions during the movement of shaft 12 in one direction while ratcheting backwardly over the cam surface 20 of shaft 12 in the other direction.

In the structure shown, a single shaft 12 which is integral is employed not only as the torque shaft but as a ratcheting means, the main operating parts being the single shaft and the spring-urged plunger cooperating therewith. It will be understood that any number of cam surfaces 18 may be provided. I have shown four cams but the number may be varied as desired.

While in the foregoing specification, I have shown a single structure in considerable detail for the purpose of illustrating an embodiment of the invention, it will be understood that such details of structure may be varied widely by

those skilled in the art without departing from the spirit of my invention.

I claim:

5 In a torque wrench of the type having a T-shaped casing providing a shaft-receiving portion having a shaft passage therein and a handle portion having a plunger passage therein intersecting said shaft passage, a shaft rotatably received in said shaft passage and having an outer end shaped for locking engagement with an object to be rotated and having also an inner end provided with a plurality of cam surfaces, each of said cam surfaces having a depressed portion of reduced radius between a steeply curved ridge portion of rapidly increasing radius and a slightly curved ratchet portion of gradually increasing radius, a plunger slideably mounted in said plunger passage and having an inner rounded end engagedly with 10 said shape cam surfaces and adapted to seat in the said depressed portions thereof, and spring means for yieldably urging said plunger against said cam surfaces with selectively variable pressure, whereby on rotation of said handle in one direction the rounded end of said plunger is locked within one of said depressed portions against the adjacent ridge portion until a torque is developed sufficient to overcome the selected spring pressure on said plunger, while upon rotation of said handle in the opposite direction said rounded end slides out of said depressed portion onto said ratchet portion and rides over said cam surfaces.

WILLIAM H. MAYER.
